US00D619787S

(12) United States Design Patent
Segretario

(10) Patent No.: US D619,787 S
(45) Date of Patent: * Jul. 20, 2010

(54) HEAD APPAREL

(76) Inventor: Sunday Segretario, 166 Ice House Rd., #10, Oakville, CT (US) 06779

() Term: 14 Years

(21) Appl. No.: 29/318,494

(22) Filed: May 21, 2008

(51) LOC (9) Cl. 02-03

(52) U.S. Cl. D2/868; D2/889

(58) Field of Classification Search D2/865, D2/866, 869, 870, 878, 889, 980, 981, 982, D2/983, 984, 985, 986, 987, 988, 989, 990, D2/991, 992, 994; 2/171, 195.8, 200.1, 239, 2/240, 241, 242; 66/172 E, 178 A, 178 R, 66/184, 185, 186, 187, 197
